US00D424608S

United States Patent [19]

Yorifuji et al.

[11] Patent Number: Des. 424,608

[45] Date of Patent: ** May 9, 2000

[54] **PHOTOSENSITIVE DRUM CASING FOR AN ELECTRONIC COPYING MACHINE**

[75] Inventors: **Takao Yorifuji; Noriki Ono**, both of Higashiyamato; **Moriyuki Kuroku**, Higashimurayama, all of Japan

[73] Assignees: **Casio Computer Co., Ltd.; Casio Electronics Manufacturing Co., Ltd.**, both of Tokyo, Japan

[**] Term: **14 Years**

[21] Appl. No.: **29/085,155**

[22] Filed: **Mar. 18, 1998**

[51] LOC (7) Cl. **16-03**

[52] U.S. Cl. **D18/40**

[58] Field of Search **D18/40, 43, 56; 355/1, 55; 399/59, 71, 74, 103, 110-112, 114, 116, 117, 119, 222, 227, 256, 258, 259, 299, 303, 358**

[57] CLAIM

The ornamental design for a photosensitive drum casing for an electronic copying machine, as shown.

DESCRIPTION

FIG. 1 is a front elevational view of a photosensitive drum casing for an electronic copying machine, showing our new design;

FIG. 2 is a top plan view thereof;

FIG. 3 is a right side elevational view thereof;

FIG. 4 is a bottom plan view thereof;

FIG. 5 is a rear elevational view thereof; and,

FIG. 6 is a left side elevational view thereof.
